(57) **CLAIM**

The ornamental design for an instrument panel register, as shown and described.

DESCRIPTION

FIG. 1 is a perspective view from the front of the instrument panel register showing our new design in a fully open position;

FIG. 2 is a perspective view from the back thereof;

FIG. 3 is a front view thereof;

FIG. 4 is a back view thereof;

FIG. 5 is a side view of a first side thereof;

FIG. 6 is a side view of a second side thereof;

FIG. 7 is a top view thereof;

FIG. 8 is a bottom view thereof;

FIG. 9 is a front perspective view thereof, showing the instrument panel register in a first fully closed position;

FIG. 10 is a front perspective view thereof, showing the instrument panel register in a second fully closed position; and,

FIG. 11 is a front perspective view of a register shown on a greatly reduced scale with like registers installed in an instrument panel.

The broken lines showing of environment are for illustrative purposes only and form no part of the claimed design.
